VACUUM RELIEF DEVICE FOR ENGINES

Charles O. Guernsey, Yeadon, Pa.

Application May 14, 1936, Serial No. 79,739

19 Claims. (Cl. 123—124)

This invention relates to vacuum relief devices in general and in particular to such devices for use on automotive engines.

It is well known that motor vehicles, especially buses, emit a large volume of objectionable and dangerous gases at periods of engine retardation such as occurs during gear changing, coasting and stopping.

These gases tend to follow the vehicle due to the turbulence of the air and finally enter the vehicle to cause discomfort and even sickness among the passengers. The excessive discharge of partly burned gases is due to the fact that an extremely high vacuum is established in the intake manifold when the main throttle is closed, which high vacuum sucks in a substantial quantity of fuel which cannot be burned due to the lack of sufficient air to make an explosive mixture in the cylinders. If the vacuum is relieved then the amount of fuel drawn in by the engine will be small and with the supply of air to the cylinders increased then the gases even if ignited will be completely burned.

It is an object of this invention, therefore, to supply a relief device which will automatically reduce the vacuum in the intake manifold.

Another object of the invention is the provision of a simple, efficient relief valve for supplying fresh air to the intake manifold at such a position as to relieve the suction acting on the carburetor.

A further object of the invention is the provision of a vacuum relief device which automatically relieves the vacuum within the intake manifold and at the same time annuls or shunts a portion of the ignition circuit to the engine.

A still further object of the invention is the provision of a vacuum relief device which automatically opens to relieve the vacuum in the intake manifold when it reaches a certain value yet which automatically closes when the vacuum has been reduced to a value materially below that at which the valve opened.

These and other objects of the invention will be apparent to one skilled in the art from a study of the following description and accompanying drawings, in which

Figure 1 is a sectional view of the device taken substantially on the central plane thereof;

Fig. 2 is a sectional view taken on line 2—2 of Fig. 1;

Fig. 3 is a sectional view taken on line 3—3 of Fig. 1 and showing the manner of securing the device to the intake manifold;

Figs. 4 and 5 are sectional views taken on lines 4—4 and 5—5 respectively of Fig. 1;

Fig. 6 is a sectional view similar to Fig. 2 but showing a slight modification thereof;

Fig. 7 is a sectional view similar to Fig. 2 but showing a still further modification;

Fig. 8 is a sectional view similar to Fig. 1 but showing a modified form of valve;

Fig. 9 is a sectional view taken on line 9—9 of Fig. 8 and showing the port arrangement, and 10

Fig. 10 is a diagrammatic view showing the electrical connection of the valve with respect to the ignition circuit.

Referring now to the drawings in detail, it is seen that the relief device or valve device A is fastened to the intake manifold B by means of a reducer 2 secured to the manifold and carrying stud bolts 4 receiving the clamping segments 6 which bear against flange 8 of eductor pipe 10. The connections between the pipe and reducer and between the reducer and manifold are suitably sealed by gaskets G. It may be stated here that the connection is made to the intake manifold of the engine at any suitable place between the throttle valve and intake valves. 25

The eductor pipe is formed as part of operating valve casing 12 which is provided with a cylinder 14 having communication with the eductor pipe through reduced opening or orifice 16 and the casing has a passage 18 connecting the eduction pipe with the cylinder through opening 20. Hollow piston 22 is arranged in the cylinder and has a head portion 24 with a central portion 25 of increased thickness in which is received and clamped a projecting stem 26. 35 Spring 28 is disposed within the piston and has one end bearing upon the head adjacent the central portion, while the other end engages a bearing member 30 secured to threaded stem 32 provided with a notched or other suitable head 33. 40 The stem has threaded engagement with a closure cap 34 held in place by fasteners 35 and the stem may be locked in any desired position by lock nut 36 as well as by protecting cap 38. It is obvious that by turning the stem 32 the compression of the spring will be varied thus adjusting the point at which the piston will move. 45

The operating or control valve casing is provided with projections 40 adapted to receive bolts 41 securing an inlet valve casing 42 thereto in 50 such a position as to close the open or head end of the control valve casing. The inlet valve casing is formed with an inlet opening 44 giving free access to chamber 46 formed by transverse webs 48 and 50. The web 48 is formed with a bearing 55

portion 52 adapted to receive and support the stem 54 of an inlet valve having a head portion 56 with bevel shoulders 58 engaging the bevel seats 60 of an opening 62 formed in web 50. The inlet valve opens inwardly of the control valve cylinder and is normally held in its seated position by the stud or projection 26 which bears upon the inlet valve head under action of the spring.

The inlet valve stem projects beyond the web 48 and is provided with an insulating block 64 threaded on the stem and with a metallic block 66 held in place by nut 68. A removable cap 70 carries contactors 72, one of which is connected to the valve casing and, therefore, grounded, while the other is connected by wire 74 to primary side of the ignition coil as will be explained later in connection with Fig. 10. It is, of course, obvious that when the valve 56 is seated the wire 74 is insulated from ground by the block 64, while when the valve is open the wire will be grounded through the contactors and block 66.

The operation of the device is as follows: Assuming the engine to be running at a relatively high speed with throttle open, then the vacuum in the inlet manifold will be relatively low and the valves will remain in the position shown in Fig. 1 blocking the inlet, since the vacuum is not sufficient to allow atmospheric pressure to operate the valves. When the engine speed is to be reduced by closing the throttle then, due to the pumping action of the engine, a high vacuum will be established in the intake manifold and in the operating valve chambers which will cause the atmospheric pressure acting on inlet valve head 56 to unseat the inlet valve, compress the spring 28 and at the same time reduce the vacuum in the chamber adjacent the piston 24 causing an unbalanced force on the piston which will move the piston to the left as viewed in Fig. 1. The orifice 16 is so chosen with respect to the opening 62 that a pressure of some value between atmospheric and manifold pressure will be present on one side of the piston which, coupled with the reduced pressure on the opposite side of the piston will hold the piston in the release position. It is to be noted that the passage 18 connecting the one side of the piston with the eductor pipe terminates above the orifice in a region of vacuum which will normally be higher than that existing in the intake manifold due to the kinetic energy of the inflowing air. As the engine slows down and the pumping action decreases the manifold vacuum will decrease and the air flow decreasing likewise will finally cause the pressures acting on the piston to be sufficiently balanced as to permit the spring to act and close the inlet valve. It will be obvious that the valve will open rapidly under high vacuum and also close rapidly under reduced vacuum and once closed will not open again until a high vacuum is reestablished, this being due to the choice of openings and the fact that opening pressure acts only on the valve head 56 to counteract the spring, while after the valve has opened it is held open not only by the differential pressures acting on the piston head, but also by the kinetic energy of the incoming air acting on the valve and piston head.

The range between opening and closing pressures may be regulated by modifying the orifice 16 and this is readily accomplished as is shown in Fig. 6 by using a removable disc 76 with opening 78 and the disc is held in place by ring 80 clamped by set screw 82. The orifice may be

changed readily by changing the disc and substituting a disc of desired opening.

The modification shown in Fig. 7 discloses a Venturi member 85 placed in the eductor pipe and held in place by set screw 86 with the opening 88 in alignment with the passage 18. This arrangement gives an even greater range in unbalanced pressures as well as an arrangement wherein adjustment is readily accomplished by interchange of Venturi elements.

The operation of the device is exactly the same when using the arrangements shown in Figs. 6 and 7 as that explained in connection with Figs. 1 to 5 inclusive, and in any case the inward movement of the inlet valve annuls or shunts the ignition circuit causing the engine speed to be more rapidly reduced thereby reducing the period in which gases are expelled by the engine. The annuling or shunting of the ignition also insures that the gases that are expelled will not be dangerous, since no combustion can occur.

Reference is now had to Figs. 8 and 9 wherein a slightly modified valve is disclosed which operates on the same principle as the previously described valve but in which parts have been combined in order to provide a lighter and less expensive valve. The valve as shown is provided with an end housing or outlet portion 90 adapted to be connected to the engine manifold B (not shown) in any suitable manner and to the valve casing 92 by bolts or other means 94. The central portion of the end housing is threaded to receive a clamping bolt 95 adapted to be locked by nut 96 in the proper position.

The valve casing is formed at one end with shoulders 98 adapted to receive a ring or orifice controlling member 100 which corresponds to the orifice of the previously described valve, and this ring is clamped between the valve casing and end housing or outlet portion by the bolts 94. It is, of course, obvious that various sizes of rings may be used exactly as various sized orifices were used in the valve of Figs. 1 to 7 inclusive. The shouldered end of the casing is substantially closed by partition 102 formed with a central opening 104 surrounded by valve seat 105. Lugs 106 extend outwardly from the partition in spaced relation to the inlet opening and are spaced apart to provide openings 108 therebetween permitting passage of air from the inlet opening to the annular chamber or space 110. The spaced lugs are connected by ring or cylinder 112 spaced from the walls of the end housing and valve casing to provide an eductor space or pipe 114 corresponding in purpose and function to the eductor pipe described in connection with Figs. 1 to 7 inclusive and from the orifice ring to provide an annular passage or orifice 115.

The cylinder is closed by head plate 116 and gasket 117 held in place by the clamping bolt 95 previously referred to and the one end of the cylinder is connected by a plurality of passages 118 to the eductor space or pipe 114. A combined piston and inlet valve 120 is arranged within the cylinder and is formed with edge portions 121 adapted to slidably engage the cylinder and with valve face 122 adapted to engage the valve seat 105. Partition 124 extends across the valve casing in spaced relation to provide an air inlet chamber 125 and the partition is formed with a bearing portion 126 adapted to receive and support valve stem 128 connected at one end to the combined piston and inlet valve and carrying at the other end a nut 130 providing an adjustable stop for spring cap 132. A spring 75

134 has one end engaging the cap, while the other end abuts the partition 124 and thus acts as a compression spring to normally retain the inlet valve upon its seat.

5 It is thus seen that the valve is very similar to the valve of Figs. 1 to 7 inclusive in that the passages 118 connect one end of the cylinder to the eductor space at a point beyond the annular passage or orifice 115 and that the other end of 10 the cylinder is connected by the openings 108 and the orifice to the manifold.

A removable cap 136 carries contactors 138 and 140, the first being connected to the cap and, therefore, grounded by means of pivot block 142 15 and compression spring 144, while the latter is insulated from the cap and connected by wire 145 to the primary side of the ignition coil. Removable plate 143 permits adjustments of the contactor points. The valve stem is provided 20 with an adjustable extension 146 which when the inlet valve is seated will maintain the contactors in spaced relation, while when the inlet valve is unseated the contactors meet each other and the ignition circuit is nullified or shunted.

25 The operation of the valve is exactly similar to that previously described, however, to avoid confusion a brief description will be given. Assuming the parts to be in the position shown in Fig. 8, upon the establishment of a high vacuum 30 in the manifold the air pressure acting on the inlet valve face will move the valve toward open position against the compression of the spring 134. The unseating of the inlet valve will permit air to rush through openings 108 and orifice 35 115 and across the passages 118, thus maintaining a slightly lower pressure in the end of the cylinder than in the manifold due to the kinetic energy of the inflowing air. The kinetic energy or impact of the incoming air acting on the inlet 40 valve and piston face will also aid in holding the inlet valve open until such time as the manifold vacuum is reduced sufficiently to permit closing of the valve under action of the spring. As soon 45 as the valve is reseated it will remain seated until a high vacuum is reestablished in the manifold.

In order to more fully describe the operation 50 of the electrical connections used in conjunction with the valve reference is had to Fig. 10 where- 55 in the usual distributor 150 is connected to the high tension coil 152 of the ignition coil as is customary. The low tension or primary coil 154 is connected to one side of the grounded battery and to ground through the breaker points 156 60 operated by cam 158. The valve contactors are connected by wire 145 as previously mentioned to the primary circuit at a point 160 between the breaker points and ignition coil. It is thus seen that the valve contactors will shunt the breaker points and so reduce the intermittent current flowing through these points as to prevent induction of sufficient voltage in the high tension coil to operate the spark plugs. The ignition circuit is, therefore, not broken but merely nullified or shunted and in case the valve contactors failed to operate or became disconnected it would have no effect on the ignition circuit. The valve of Figs. 1 to 7 inclusive is connected 65 70 into the circuit in exactly the same manner as just described and will, of course, operate in the same manner.

75 It is, of course, obvious that various changes may be made in the device and such changes are contemplated as fall within the scope of the

appended claims which define what petitioner believes to be his invention.

What is claimed is:

1. A vacuum relief device for the intake mani- 5 folds of internal combustion engines comprising, a cylinder, a piston reciprocable therein, an inlet valve having a closing movement effected by said piston, means spacing said inlet valve and piston, passages connecting both ends of said cylinder with the manifold, and one of said passages 10 being provided with a reduced portion whereby upon the opening of said inlet valve under relatively high manifold vacuum unequal pressures are established on opposite sides of said piston to retain the same in a predetermined position. 15

2. A vacuum relief device for the intake mani- 20 folds of internal combustion engines comprising, a cylinder, a piston reciprocable therein, an inlet valve having a closing movement effected by said piston, means spacing said inlet valve and 25 piston, resilient means normally retaining said inlet valve closed, passages connecting both ends of said cylinder with the manifold to normally establish equal pressures on either side of said piston, and restricting means in one of said 30 passages whereby upon the opening of said inlet valve under relatively high manifold vacuum unequal pressures are established on opposite sides of said piston to retain the same in a predetermined position. 35

3. A vacuum relief device for the intake mani- 40 folds of internal combustion engines comprising, a cylinder, a piston reciprocable therein, an inlet valve in spaced relation to said piston, means nor- 45 mally retaining said valve closed, passages connect- 50 ing both ends of said cylinder with the manifold, said inlet valve opening at a relatively low manifold pressure to admit air to said manifold, and restricting means in one of said passages 55 whereby upon opening of the inlet valve unequal pressures are established on opposite sides of said piston to prevent closing of said valve until a substantially higher manifold pressure has been established. 60

4. A vacuum relief device for the intake mani- 65 folds of internal combustion engines comprising, a cylinder, a piston reciprocable therein, an inlet valve in spaced relation to said piston, means nor- 70 mally retaining said valve closed, passages connect- 75 ing both ends of said cylinder with the manifold, said inlet valve opening at a relatively low manifold pressure to admit air to said manifold, and restricting means in one of said passages 80 whereby upon opening of the inlet valve unequal pressures are established on opposite sides of said piston to prevent closing of said valve until a substantially higher manifold pressure has been established, said first named means being adjustable to control the opening and closing of said valve. 85

5. A vacuum relief device for the intake mani- 90 folds of internal combustion engines, comprising, a cylinder, a piston reciprocable therein, an inlet valve in spaced relation to said piston, means nor- 95 mally retaining said valve closed, passages connect- 100 ing both ends of said cylinder with the manifold, said inlet valve opening at a relatively low manifold pressure to admit air to said manifold, and restricting means in one of said passages 105 whereby upon opening of the inlet valve unequal pressures are established on opposite sides of said piston to prevent closing of said valve until a substantially higher manifold pressure has been established, said restricting means being variable 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

- in order to control the range between opening and closing pressures of said valve.
6. A vacuum relief device for the intake manifolds of internal combustion engines comprising, 5 a cylinder, a piston reciprocable therein, an inlet valve having a closing movement effected by said piston, means spacing said inlet valve and piston, an eduction pipe connecting one end of said cylinder with the manifold, a portion of said eduction pipe adjacent the cylinder being of restricted area, and a passage connecting the other end of said cylinder with the pipe beyond said restriction.
7. A vacuum relief device for the intake manifolds of internal combustion engines comprising, 15 a cylinder, a piston reciprocable therein, an inlet valve having a closing movement effected by said piston, means spacing said inlet valve and piston, an eduction pipe connecting one end of said cylinder with the manifold, restricting means in said eduction pipe adjacent the cylinder, and a passage connecting the other end of said cylinder with the pipe at a point beyond said restricting means.
8. A vacuum relief device for the intake manifolds of internal combustion engines comprising, 20 a cylinder, a piston reciprocable therein, an inlet valve having a closing movement effected by said piston, means spacing said inlet valve and piston, an eduction pipe connecting one end of said cylinder with the manifold, venturi means in said pipe adjacent the cylinder, and a passage connecting the other end of said cylinder with the throat portion of the venturi.
9. A vacuum relief device for the intake manifolds of internal combustion engines comprising, 25 a cylinder, a piston reciprocable therein, chambers at either side of said piston, a valve controlling an inlet into one of said chambers, means operatively associated with said valve and piston for causing joint operation thereof in at least one direction, passages connecting each of said chambers with said manifold, one of said passages having a portion of restricted area between the 30 associated chamber and the junction with the other passage.
10. A vacuum relief device for the intake manifolds of internal combustion engines comprising, 35 a cylinder, a piston reciprocable therein, chambers at either side of said piston, an inlet valve opening into one of said chambers, means operatively associated with said valve and piston for causing joint operation thereof in at least one direction, passages connecting each of said chambers with said manifold, one of said passages having a portion of restricted area between the 40 associated chamber and the junction with the other passage, and means secured to said inlet valve for shunting the ignition circuit of the engine.
11. A vacuum relief device for the intake manifolds of internal combustion engines comprising, 45 a cylinder, a piston reciprocable therein, an inlet valve having a closing movement effected by said piston, means spacing said inlet valve and piston, 50 passages connecting both ends of said cylinder with the manifold, and one of said passages being provided with a reduced portion whereby upon the opening of said inlet valve unequal pressures are established on opposite sides of said piston, 55 said inlet valve having means connected thereto for annulling the ignition circuit of the engine.
12. A vacuum relief device for the intake manifolds of internal combustion engines comprising, 60 a cylinder, a piston reciprocable therein, an inlet valve, passages connecting both ends of said cyl-
- inder with the manifold, and one of said passages being provided with a reduced portion whereby the opening of said inlet valve under high manifold vacuum produces unequal pressures on opposite sides of said piston to retain the valve in the 5 open position.
13. A vacuum relief device for the intake manifolds of internal combustion engines comprising, 10 a cylinder, a piston reciprocable therein, an inlet valve, means normally retaining said inlet valve closed, passages connecting both ends of said cylinder with the manifold to normally establish equal pressures on either side of the piston, and restricting means in one of the passages whereby upon the opening of said inlet valve under high manifold vacuum unequal pressures are established on opposite sides of said piston to retain the inlet valve in open position against the action of said first named means.
14. A vacuum relief device for the intake manifolds of internal combustion engines comprising, 15 a cylinder, a piston reciprocable therein, an inlet valve, means normally retaining said inlet valve closed, passages connecting both ends of said cylinder with the manifold, said inlet valve opening at a relatively low manifold pressure to admit air to said manifold, and restricting means in one of said passages whereby the opening of the inlet valve produces unequal pressures on opposite sides of said piston to retain the inlet valve in open position against the action of said first named means until a substantially higher manifold pressure has been established.
15. A vacuum relief device for the intake manifolds of internal combustion engines, 20 comprising, a cylinder, a piston reciprocable therein, an inlet valve, means normally retaining said inlet valve closed, passages connecting both ends of said cylinder with the manifold to normally establish equal pressures on either side of the piston, and restricting means in one of the passages for directing a high velocity stream of air across the other of said passages whereby the valve is retained in open position due to the kinetic energy of the inflowing air after the 25 inlet valve has been opened by atmospheric pressure.
16. A vacuum relief device for intake manifolds of internal combustion engines comprising, 30 an inlet valve, a cylinder, a piston reciprocable therein and operatively associated with said inlet valve, means normally retaining said valve closed, said valve opening under atmospheric pressure against the action of said means upon establishment of a relatively low manifold pressure, and means establishing unequal pressures on opposite 35 sides of said piston upon opening of said valve to permit utilization of the kinetic energy of the inflowing air for retaining said inlet valve open until a relatively higher manifold pressure has 40 been established.
17. A vacuum relief device for intake manifolds of internal combustion engines comprising, 45 an inlet valve operable by unbalanced pressures, a cylinder, a piston reciprocable therein and operatively associated with said inlet valve, said inlet valve opening upon the establishment of highly unbalanced pressures caused by the engine suction to admit air to the manifold, and means establishing unequal pressures on opposite sides 50 of said piston upon opening of said valve to permit utilization of the kinetic energy of the inflowing air for retaining the valve in open position until the establishment of but slightly unbalanced pressures.

18. A vacuum relief device for intake manifolds of internal combustion engines comprising, a cylinder, a combined piston and inlet valve reciprocable therein, chambers at either side of said piston, passages connecting each of said chambers with said manifold, means in one of said passages providing a portion of restricted area between the associated chamber and the junction with the other passage.
- 5 19. A vacuum relief device for intake manifolds of internal combustion engines comprising, a cylinder, a piston reciprocable therein, an inlet valve formed on one face of said piston, chambers at either side of said piston, said inlet valve controlling an entrance to one of said chambers, passages connecting each of said chambers with said manifold, and means in one of said passages providing a portion of restricted area between the associated chamber and the junction with the other passage.
